DESIGN FOR TONGS

Elwood K. Sechrist and Donald T. Offord,
Detroit, Mich.

Application May 22, 1947, Serial No. 139,212

Term of patent 7 years

(Cl. D44—29)

To all whom it may concern:

Be it known that we, Elwood K. Sechrist and Donald T. Offord, citizens of the United States, residing at Detroit, in the county of Wayne and State of Michigan, have invented a new, original, and ornamental Design for Tongs, of which the following is a specification, reference being had to the accompanying drawing, forming part thereof, wherein:

Fig. 1 is a top plan view of a tongs, showing our new design.

Fig. 2 is a side elevational view.

Fig. 3 is a view similar to Fig. 2, but showing the jaws open.

Fig. 4 is a cross sectional view taken on the line 4—4 of Fig. 2.

Fig. 5 is a cross sectional view taken on the line 5—5 of Fig. 2.

Fig. 6 is a cross section on the line 6—6 of Fig. 2.

We claim:

The ornamental design for tongs, as shown.

ELWOOD K. SECHRIST.

DONALD T. OFFORD.
